UNITED STATES PATENT OFFICE.

RICHARD MURRAY, OF NEW YORK, N. Y.

SHOE-TREE.

1,163,947.

Specification of Letters Patent. Patented Dec. 14, 1915.

Application filed May 21, 1915. Serial No. 29,465.

To all whom it may concern:

Be it known that I, RICHARD MURRAY, a citizen of the United States, and residing at New York, in the county of New York and State of New York, have invented certain new and useful Improvements in Shoe-Trees, of which the following is a specification, such as will enable those skilled in the art to which it appertains to make and use the same.

This invention relates to shoe trees, and the object thereof is to provide an improved device of this class, the front or toe portion of which may be expanded laterally in order 15 to stretch the corresponding part of the shoe and provide room for the toes; and with this object in view the invention consists in a device of the class specified, constructed and operated as hereinafter described and 20 claimed.

The invention is fully disclosed in the following specification, of which the accompanying drawing forms a part, in which the separate parts of my improvement are 25 designated by suitable reference characters in each of the views, and in which:—

Figure 1 is a plan view of my improved shoe tree with part of the construction broken away and indicating the method of 30 operation; Fig. 2 a sectional side view thereof; and Fig. 3 a detail view partially in section of an expanding device which I employ.

In the practice of my invention, I provide a shoe tree *a* divided transversely at *a*² to 35 form a heel portion *b* and a toe portion *c*, and the toe portion *c* is divided longitudinally to form a main inner part *c*² and a supplemental outer side part *c*³. The outer side part *c*³ is on the outer side of the tree, or 40 the toe portion thereof, and is separated from the inner part *c*² in or by a vertical plane *c*⁴ passing longitudinally through said toe portion and diverging backwardly to the rear end of the toe portion *c* at which point 45 the outer side part *c*³ and the inner side part *c*² are hinged together at *d*, the hinge consisting of a shorter plate *d*² and a longer plate *d*³, said plates being secured respectively to the parts *c*² and *c*³ by means of 50 screws *d*⁴ or in any other suitable manner.

The rear end of the parts *c*³ is beveled as shown at *c*⁵ and the inner face thereof is provided, preferably, slightly forward of the transverse middle thereof with a recess 55 *c*⁶ having a front beveled or inclined wall *c*⁷ and the hinged plate *d*³ which is hinged to

the parts *c*³ of the toe portion of the tree overlaps the recess *c*⁶, or the rear end portion thereof.

Formed in the rear end of the part *c*² of the toe portion of the tree is a conical recess *e* having a forward extension *e*², and forwardly of the extension *e*² of the recess *e* the part *c*² is provided with a longitudinal bore *f* which communicates with the extension *e*² of the recess *e* at its rear end and the front end portion of which opens through the inner face of the part *c*² and communicates with the recess *c*⁸, and mounted in the bore *f* is a longitudinally movable lock and 65 spreader device *g* provided at its rear end with a threaded stem *g*² which passes through the extension *e*² of the recess *e*, and at its front or outer end with a head *g*³ provided with a V-shaped prong *g*⁴ which enters the 70 recess *c*⁶ and the end wall *g*⁵ of which is beveled to correspond with the beveled front wall *c*⁷ of the recess *c*⁶.

In the construction shown, the stem *g*² of the lock device and spreader *g* is enlarged 80 adjacent to the head *g*³ thereof as shown at *g*⁶, to form a shoulder *g*⁷ and the outer wall of the bore *f* is similarly formed and provided with a corresponding shoulder *f*².

The threaded end of the stem *g*² of the 85 lock device and spreader *g* is provided with a cylindrical head *h* which is tubular in form and provided with an interior thread and adapted to be screwed onto the stem *g*², 90 as clearly shown in Figs. 2 and 3.

The front part of the heel portion *b* of the tree and the rear part of the toe portion *c*, or the inner side part *c*² thereof are provided with longitudinal recesses *i* in 95 which is placed a link device *j* pivoted to both of said parts as shown at *j*², and the heel portion *b* is provided with a handle *k* which is secured thereto, or to the top thereof, or connected therewith in any desired manner.

With the parts of my improved tree in the position shown in full lines in Fig. 1, the said tree may be used in the same manner as other devices of this class and may be inserted into, or removed from the shoe whenever desired, but when it is desired to spread the toe portion of the shoe on the outer side thereof, the heel portion of the tree is raised and the toe portion is inserted into the shoe and the head *h* of the stem *g*² 110 of the lock device and spreader *g* is turned so as to withdraw said head partially from

said stem and so that said head will project beyond the rear end of the toe portion *c* of the tree, after which the heel portion *b* of the tree is forced downwardly into the 5 shoe, and in this operation said heel portion bears on the head *h* and forces the lock device and spreader *g* forwardly, and this operation forces the part *c*³ of the toe portion of the tree outwardly, as indicated 10 in dotted lines in Fig. 1, and this stretches the toe portion of the shoe, as will be readily understood, and when said toe portion of the shoe has been stretched sufficiently the heel portion of the tree is raised and the head *h* 15 of the stem *g*² of the spreader and lock device is turned in the opposite direction, and this draws the part *c*³ of the toe portion of the tree inwardly into the position shown 20 in full lines in Fig. 1, after which the tree may be easily removed from the shoe in the usual manner.

When the parts are in position shown in full lines in Fig. 1, the head *g*³ of the lock device and spreader *g* secures and holds 25 the part *c*³ closely adjacent to the part *c*² of the toe portion of the tree, and in this operation it engages the front end of the hinge plate *d*³, and while I have shown and described the construction which I prefer 30 my invention is not limited to the exact details thereof, herein shown and described, and various changes therein and modifications thereof, may be made, within the scope of the appended claims, without departing 35 from the spirit of my invention or sacrificing its advantages.

Having fully described my invention, what I claim as new and desire to secure by Letters Patent, is:—

40 1. A shoe tree divided transversely into

toe and heel portions the adjacent ends of which are loosely connected at the top thereof, said toe portion being divided longitudinally into outer and inner side portions which are hinged together at their 45 rear ends, and a lock device and spreader movable longitudinally through one of said side portions and adapted to engage the other, that side portion in which the lock device and spreader is movable being provided at its rear end with a recess and said lock device and spreader with a threaded stem which passes into said recess and is provided with a threaded head which is longitudinally movable thereon. 50 55

2. A shoe tree divided transversely into toe and heel portions the adjacent ends of which are loosely connected at the top thereof, the toe portion being divided longitudinally into outer and inner side portions which are hinged together at their rear ends, and a lock device and spreader movable longitudinally through one of said side portions and adapted to engage the other, that side portion in which the lock 60 device and spreader is movable being provided at its rear end with a recess and said lock device and spreader with a stem which passes into said recess and is provided with a head on which the heel portion when in 65 a horizontal position is adapted to bear.

In testimony that I claim the foregoing as my invention I have signed my name in presence of the subscribing witnesses this 19th day of May, 1915.

RICHARD MURRAY.
